[57] CLAIM

The ornamental design for a cover for a baking dish or the like, as shown and described.

DESCRIPTION

FIG. 1 is a top plan view of a cover for a baking dish or the like showing my new design.

FIG. 2 is a front elevational view, with the rear elevational view being identical.

FIG. 3 is a bottom plan view.

FIG. 4 is an elevational view in section taken along line
4—4 of FIG. 1.

FIG. 5 is an end elevational view, with the opposite end elevational view being identical.

FIG. 6 is an enlarged fragmental sectional view in elevation of a portion of the cover shown in FIG. 4.
